UNITED STATES PATENT OFFICE.

EDWARD WALBAUM, OF WEBSTER, SOUTH DAKOTA.

RIDING ATTACHMENT FOR PLOWS.

No. 857,503.

Specification of Letters Patent.

Patented June 18, 1907.

Application filed November 26, 1906. Serial No. 345,112.

To all whom it may concern:

Be it known that I, EDWARD WALBAUM, a citizen of the United States, residing at Webster, in the county of Day and State of South Dakota, have invented certain new and useful Improvements in Riding Attachments for Plows, of which the following is a specification.

This invention consists of a simple form of riding attachment which is designed to be applied to various types of walking plows and the essential features of the invention reside in the peculiar construction employed which conduces to simplicity, admits of varied adjustment of the plow, and which is generally advantageous from the standpoint of practical use as will be apparent on references to the detail description hereinafter.

For a full understanding of the invention and the merits thereof and also to acquire a knowledge of the details of construction of the means for effecting the result, reference is to be had to the following description and accompanying drawings, in which:

25 Figure 1 is a rear elevation of a plow showing the attachment applied thereto. Fig. 2 is a top plan view of the invention applied. Fig. 3 is a view similar to Fig. 1, the plow being shown in the position assumed thereby 30 when the share is out of the ground, as when the implement is being turned.

Corresponding and like parts are referred to in the following description and indicated in all the views of the drawings by the same 35 reference characters.

Specifically describing the invention, the drawing illustrates a conventional type of breaking plow embodying the usual share 1, moldboard 2, beam 3 and handles 4. The 40 attachment comprising the invention consists of a laterally arranged wheel supporting beam 5, one end of which is pivotally connected as shown at 5^a, with the rear end portion of the beam 3, and the outer end of 45 which has the ground wheel 6 mounted thereon. A suitable seat 7 for the driver of the implement is applied to the wheel supporting beam 5 near the outer end portion thereof, and this portion of said beam 5 is connected with the front end portion of the beam 3, by means of a draft bar 8. The draft bar 8 may be directly secured to the clevis 9 ordinarily located at the front end 50 of the longitudinal beam 3 of all plows. Secured to and projecting upwardly from the beam 5 intermediate of the ends of the lat-

ter, is a plate 9, the upper portion of which is notched to form a segment 10 coöoperating with a hand operated latch which is applied to a hand lever 11 pivoted at the lower end 60 thereof as shown at 12, to said beam 5. The lever 11 may be held in an adjusted position by means of the latch applied thereto, and said lever is connected at a point between its ends with a rod 13, the outer end of which is 65 formed with a hook 14 adapted for adjustable connection with a plate 15 attached to the upper portions of the handles 4 of the plow. The plate 15 is provided at intervals in its length with a plurality of openings 16 70 into which the hook 14 of the rod 13 is adapted to enter to connect the plate 15 with the lever 11.

It will be apparent from the foregoing that the operator sitting on the seat 7 may readily 75 operate the lever 11 so as to adjust the plow with reference to the attachment and thereby regulate the depth of the cutting action of the share 1. The rod 13 is readily detachable from the plate 15 and this is necessary 80 and advantageous in order to admit of throwing the share 1 out of the ground to facilitate turning of the plow.

In actual operation, the position of the parts is substantially as shown in Fig. 1. 85 When it is desired to turn the plow, the rider on the seat 7 will get off of said seat and detach the hook 14 from the plate 15, permitting the plow by pivotal movement, to swing to one side as shown in Fig. 2, and thereby 90 throw the share 1 out of the ground. The parts may be readily connected for operation as soon as the plow has turned and in an evident manner.

It will be apparent from the foregoing that 95 the operation of the device may be very easily performed at the expense of a minimum amount of labor on the part of the rider, especially on account of the construction of the mechanism whereby the point of 100 pivotal connection of the beam 5 is situated at a considerable distance from the point of pivotal connection of the rod 13 established by the hook 14 engaging in one of the openings 16. In other words the connection of 105 the rod 13 is such that considerable leverage is secured in effecting adjustment of the plow relatively to the beam, and this is of considerable advantage for obvious reasons.

Having thus described the invention, what 110 is claimed as new is:

In a device of the character described, the

combination of a plow comprising a beam and a pair of spaced handles, a cross bar connecting the handles, a laterally extending beam having its inner end pivotally connected to the plow beam, a wheel mounted upon the outer end of the said beam, a plate secured to the beam and formed with a toothed edge, an operating lever pivotally connected to the beam, a latch carried by the operating lever and engaging the toothed edge of the plate, a rod loosely connected to the operating lever and having an adjustable connec-

tion with the before mentioned cross bar connecting the plow handles, and a draft bar connecting the outer portion of the laterally extending beam with the forward portion of the plow beam. 15

In testimony whereof I affix my signature in presence of two witnesses.

EDWARD WALBAUM. [L. s.]
